FIG. 1 is a top plan view of a traffic signal casing, showing our new design;

FIG. 2 is a front face view thereof;

FIG. 3 is an end elevation view thereof, illustrating the left end;

FIG. 4 is a vertical section substantially on the line 4—4 of FIG. 2; and

FIG. 5 is a vertical section substantially on the line 5—5 of FIG. 2.

The side opposite to that shown in FIG. 2 is substantially a flat or plane surface, the outline of which is a reverse or mirror image of the outline of the face shown in FIG. 2. The end opposite to that shown in FIG. 3 is substantially a reverse or mirror image of that shown in FIG. 3. The bottom surface is substantially two flat or plane rectangles.

We claim:

The ornamental design for a traffic signal casing, substantially as shown and described.
